UNITED STATES PATENT OFFICE.

WILLIAM BURNES SMEDLEY, OF SALT LAKE CITY, UTAH TERRITORY.

DESIGN FOR A GAME-BOARD.

SPECIFICATION forming part of Design No. 24,987, dated December 17, 1895.

Application filed September 20, 1895. Serial No. 563,145. Term of patent 7 years.

To all whom it may concern:

Be it known that I, WILLIAM BURNES SMEDLEY, a citizen of the United States, residing at Salt Lake City, in the county of Salt Lake and Territory of Utah, have invented and produced a new and original Design for Game-Boards; and I do hereby declare the following to be a full, clear, and exact description of the same, reference being had to the accompanying drawing, forming a part thereof.

My invention is a new and useful design for a game-board, and is illustrated in the accompanying drawing, which represents the same in plan.

The board as a whole is represented at A, and in the two upper corners has represented upon its surface mountains, and in each of the two lower corners has represented a figure. Adjacent the lower left-hand corner is a representation of the Capitol at Washington and adjacent the lower right-hand corner is the representation of a receptacle, from which is shown projecting the handle of a spoon or ladle and in which is also shown the head of a man. In the center of the upper part of the board is represented the American flag, and beginning at the point B the board is provided with raised portions corresponding in shape and extent, which portions form a labyrinth

on the surface of the board. Beginning at 30 one of said points B the raised portion is concaved to the point C and then provided with a short very-pronounced convex curve and then with a concavo-convex curve to the point D. The raised portion is then curved, as 35 shown, from E to F to G and in the space between E and F is represented on the left-hand side of the board the head and bust of a man and on the right-hand side of the board a bug. The remaining portions of the raised wall are 40 formed as shown at H, I and K, and the central portion is formed as illustrated, beginning at L, extending in almost an oblique straight line to point M, then curved sharply at N and O, then extending on a concave 45 curve to point P, then on an almost straight line to the point Q, the line P Q being parallel with the line L M, and then curved, as shown, to the point R.

I claim as my invention—

The design for a game board as herein shown and described.

In testimony whereof I affix my signature in presence of two witnesses.

WILLIAM BURNES SMEDLEY.
